ROCK DRILL

Otto J. Schorer, Northampton, Mass., assignor to Worthington Pump and Machinery Corporation, Harrison, N. J., a corporation of Delaware

Application August 29, 1941, Serial No. 408,705

1 Claim. (Cl. 255—49)

This invention relates to percussive tools and more particularly to rock drills. An object of the present invention is to provide means for controlling the delivery of cleansing fluid to the point of contact of the drill steel with the rock, such liquid serving the dual purpose of cleansing the drill hole and of wetting the rock drillings, for keeping down dust and prevention of silicosis.

More specifically, the present invention provides means controlling the delivery of the wetting liquid or water to the drill hole, operated by the throttle of the rock drill, which controls the delivery of operating pressure fluid to the drill, so that at all times during operation of the drill wetting liquid will be delivered to the drill hole.

With these and other objects in view, as may appear from the accompanying specification, the invention consists of various features of construction and combination of parts, which will be first described in connection with the accompanying drawings, showing a rock drill of a preferred form embodying the invention, and the features forming the invention will be specifically pointed out in the claim.

In the drawings:

Figure 1 is an end view of a rock drill equipped with the improved water or liquid control mechanism.

Figure 2 is a longitudinal section through the rock drill taken on the line 2—2 of Figure 1.

Figure 3 is a cross-section view through the rock drill taken on the line 3—3 of Figure 2.

Figure 4 is a detail cross-section view taken on the line 4—4 of Figure 1, showing the wetting liquid control valve in closed position.

Figure 5 is a diagrammatic view showing a slight modification of the invention and illustrating a structure wherein the quantity of wetting liquid or water delivered to the drill hole is proportionate to the percentage of full capacity operation of the drill.

Referring more particularly to the drawings, the improved rock drill structure includes a piston 1, reciprocated by means of pressure fluid in a cylinder 2 for actuating a drill steel 3. The details of the cylinder, piston and valve mechanism for controlling operation of the piston form no part of the present invention.

A throttle valve 5, actuated by means of a throttle handle 6, controls delivery of the actuating pressure fluid to the distributor control valve 7 of the rock drill structure. The drill steel 3 is provided with a longitudinally extending bore 10, which opens out through the cutting head

(not shown) of said drill steel to permit delivery of water or other suitable liquid into the drill hole. A tube or needle 11 extends from the head 8 of the rock drill longitudinally therethrough, at the axis of the drill, for delivering water or other fluid to the bore 10 of the drill steel 3.

A water connection 11 is connected to the head 8 of the rock drill and delivers water from any suitable source (not shown) to the rock drill. This water or other liquid passes through the passageway 12 in the head 8 and into the annular passageway 14 formed in the head, from which it passes through the bore or passageway 15 into the chamber 16. The chamber 16 opens into the bore 17 of the sleeve 18, and the passage of liquid from the chamber 16 into the bore 17 is controlled by a valve 19, which seats against a valve seat 20 formed in the end of the sleeve 18.

Wetting fluid from the bore 17 is delivered through a passage 21 into an annular passage 22, from whence it flows, through the radial passageway 22^a into the annular passageway 22^b. A plurality of radial passages 23 extend inwardly from the annular passageway 22^b to the inlet of the tube 11, permitting the wetting fluid to flow into and through said tube to the bore of the drill steel.

The valve 19 is held on its seat 20 by a spring 24, the tension of which may be set by means of a tension nut 26. The stem 27 of the valve 19 has an operating plunger 28 formed thereon which projects out of the outer end of the sleeve 18 and engages the perimeter of a cam 29, which latter is connected to the throttle 5 and is operated therewith by means of the throttle handle 6. The cam 29 has a plurality of notches 30, 31 and 32 cut in its perimeter which receive the tapered end 33 of the plunger 28 so as to prevent oscillation of the plunger 28 and arrest any movement of the throttle handle 6 or throttle 5 under the vibratory action created by operation of the drill steel. The notch 30 is deeper than the notches 31 and 32 and is positioned on the perimeter of the cam so that it will receive the tapered end 33 of the plunger 28 when the throttle handle 6 is in position to close the throttle and cut off the supply of pressure actuating fluid to the rock drill, at which time the valve 19 will be seated, cutting off the flow of water or other wetting fluid to and through the tube 11.

The notch 31 is positioned at a point intermediate the stop position of the throttle, corresponding to the notch 30, and the full operating

position of the throttle, as represented by the notch 32, so that when the drill is operating at partial speed or under light throttle, by reason of the fact that these notches 31 and 32 are less in depth than the notch 30, the valve 19 will be held open and water will be delivered to the drill steel and oscillation of the valve 19 and throttle 5 will be prevented.

From the foregoing it will be seen that whenever the throttle 5 is operated to admit pressure actuating fluid in any degree to the rock drill, the valve 19 will be operated to permit the flow of wetting liquid into the drill hole for wetting the dust and chippings created in the drilling operation.

Figure 5 shows a slight modification of the invention which, however, operates on exactly the same principle as the structure shown in Figures 1 to 4, differing therefrom only in that the depths of the notches 31' and 32' formed in the perimeter of the cam 29' vary, so that the valve 19' will be held off its seat 26' in varying degrees proportionate to the percentage of full capacity flow of pressure actuating fluid delivered to the rock drill. Thus the quantity of water or wetting fluid delivered to the drill hole will be in direct proportion to the percentage of full capacity operation of the rock drill.

It will be understood that the invention is not to be limited to the specific construction or arrangement of parts shown, but that they may be widely modified within the invention defined by the claim.

What is claimed is:

In a cleansing fluid control for rock drills including a rock drill having a head and a drill steel bored to deliver liquid to the cutting head thereof, a liquid tube for delivering cleansing liquid to the bore of the drill steel, a throttle valve for controlling the delivery of operating pressure fluid to the rock drill, said rock drill head provided with an annular passage-way and with a passage 5 for delivering cleansing liquid to said annular passage-way, said rock drill head provided with a second annular passage-way and passage-ways establishing communication between said second annular passage-way and the inlet end of said 10 liquid tube, said rock drill provided with a communicating passage-way establishing communication between said annular passage-ways, a valve controlling the flow of liquid from said first to said second annular passage-way through said 15 communicating passage-way, a spring for normally seating said valve, a cam actuated by movement of said throttle valve, a stem carried by said liquid control valve and engaging the perimeter of the cam for opening said liquid control valve 20 against the tension of the spring upon the opening of the throttle, said cam and stem provided with cooperating means to hold the valve in predetermined adjusted positions against oscillation by vibrations set up during operation of the rock 25 drill.

OTTO J. SCHORER.
